UNITED STATES PATENT OFFICE.

ADOLPH SAMSON, OF BUFFALO, NEW YORK, ASSIGNOR TO PRATT & LETCHWORTH, OF SAME PLACE.

MACHINE FOR ATTACHING TONGUES TO BUCKLES.

SPECIFICATION forming part of Letters Patent No. 410,770, dated September 10, 1889.

Application filed April 12, 1889. Serial No. 307,008. (No model.)

To all whom it may concern:

Be it known that I, ADOLPH SAMSON, a citizen of the United States, residing at Buffalo, in the county of Erie and State of New York, 5 have invented new and useful Improvements in Machines for Attaching Tongues to Buckles, of which the following is a specification.

This invention relates to a machine for attaching the pivoted tongues of buckles to the buckle-frame. Heretofore this has been accomplished by placing the tongue-blank against the buckle-frame and bending the end of the tongue-blank around the cross-bar of the buckle by means of a reciprocating head or plunger. This method requires the buckle to be accurately located under the plunger and to be held by an attendant during the bending operation, which consumes considerable time and renders the hands of 20 the operator liable to be injured in centering and holding the buckles under the plunger.

The object of my invention is to construct a simple machine whereby the tongues are quickly attached to the buckle, so as to effect 25 a saving in time and labor, and which requires no care or attention on the part of the operator other than to present the buckles and tongues to the machine.

The invention consists of the improvements 30 which will be hereinafter fully described, and pointed out in the claims.

In the accompanying drawings, Figure 1 is a front elevation of my improved buckle-tonguing machine partly in section. Fig. 2 is an end elevation thereof partly in section. 35 Fig. 3 is a sectional elevation, on an enlarged scale, of the compressing-die and one of the buckle-carrying dies, showing the buckle-frame and tongue in position ready to be united by the compressing-die. Fig. 4 is a similar view showing the tongue in the act of being bent or compressed. Fig. 5 is a top plan view of one of the carrying-dies.

Like letters of reference refer to like parts 40 in the several figures.

Referring to Fig. 4, A represents the frame of an ordinary buckle, consisting of side bars and connecting end or cross bars, and b is the tongue, provided at its inner end with an eye, 45 whereby it is attached to one of the cross-bars

of the buckle-frame. Before being attached to the buckle-frame the tongue-blank is given the form shown in Fig. 3, its body having the shape of that of the finished tongue, with a hook-shaped portion c at one end, which is 55 bent around the cross-bar of the buckle-frame to form the eye.

D represents the stationary frame of the machine, consisting of a horizontal bed and supporting-legs D', and D² are two parallel 60 standards secured to the bed and connected at their upper ends by a cross-piece d.

E represents a revolving vertical disk arranged on one side of the machine and mounted on a horizontal shaft e, which is 65 journaled in suitable bearings supported between the standards D², one of these bearings being designated by the letter e' in Fig. 1, and the other is shown by dotted lines in the same figure.

f represents the horizontal driving-shaft of the machine, having a driving-pulley f', and from which the revolving disk E is driven by a pinion f², secured to said shaft and meshing with a gear-wheel F, formed on or secured to 75 the rear side of the disk.

G represents carrying-dies arranged at suitable intervals on the periphery of the rotating disk E, and which form traveling supports, upon which the buckle-frames, together 80 with the tongues, are placed. These carrying-dies are provided with seats which are shaped to conform to and receive the buckle-frame and tongue. The carrying-dies represented in the drawings are provided with a 85 transverse recess g, for receiving the rear cross-bar of the buckle-frame, to which the tongue is to be attached, and with a longitudinal recess or depression g', in which the tongue fits.

H represents an oscillating compressing-die 90 arranged directly above the revolving disk E and journaled upon a horizontal arbor h, secured in the cross-piece d of the standards D². The compressing-die H is provided on its under side with a curved recess i, which bends 95 the projecting hook-shaped portion c of the tongue inwardly around the cross-bar of the buckle-frame, as represented in Fig. 4, and thereby securely fastens the tongue to the buckle-frame. The bending-recess i is ar- 100

ranged in a longitudinal rib i' , formed at the lower portion of the compressing-die. The outer ends of the buckle-carrying dies G are recessed to receive this rib when the two dies 5 come together, as clearly shown in Fig. 4.

The front advancing side of each carrying-die G is made straight and abrupt, as shown at j , and the compressing-die H is provided with a corresponding abrupt face or shoulder k , which in the normal position of the compressing-die stands in the path of the abrupt faces of the traveling dies G , so that the traveling dies will strike the shoulder of the compressing-die and swing the latter forwardly 10 on its pivot, causing the bending-recess to act upon the tongue. As soon as a carrying-die has cleared the shoulder of the compressing-die, the latter is returned to its former position by a spring l , attached at one end to the die and at its other end to the cross-piece d . The return movement of the compressing-die is limited by a projection m on the die, which strikes against a pin m' , secured to the cross-piece d , as represented in Fig. 3. 15

25 The buckle-frames to be tongued are placed face downward in the seats of the carrying-dies on the ascending side of the revolving disk E , with the free ends of the tongues resting against the front cross-bars of the buckle-frames and the hooked portions of the tongues embracing the rear cross-bars of the buckle-frame, as represented in Fig. 3. The buckles and tongues are loosely held upon the carrying-dies by the rear cross-bars of the buckles, 30 which fit in the transverse recesses g of the dies. The carrying-dies in passing successively underneath the compressing-die turn the latter in the direction in which the traveling dies move, thereby causing the bending- 35 recess i to approach the hook-shaped portions of the tongues and bending the same against the rear cross-bar of the buckle-frames. After the abrupt front side of a traveling-die has advanced out of contact with the shoulder of a compressing-die, as shown in Fig. 4, 40 the swinging movement of the compressing-die is completed by the bent eye of the tongue bearing against the front side of the bending-recess. As soon as the eye of the tongue clears 45 the bending-recess, the spring l returns the compressing-die to its original position ready to co-operate with the next succeeding carrying-die. On reaching the descending side of 50 the revolving disk E , the tongued buckles fall 55 out of the seats in the carrying-dies into a delivery-chute N , as shown in the drawings, or into a receptacle placed under the descending side of the disk.

By my improved machine the buckles are 60 tongued at a single operation in a rapid and uniform manner without requiring manipulation of the buckles in proximity to the point at which the compressing operation is effected, thereby saving considerable time and 65 labor and avoiding the liability of injury to the operator.

The arbor of the oscillating compressing-

die H is preferably arranged in a vertical slot n , formed in the cross-piece d , and clamped therein by a nut applied to the inner screw-threaded end of the arbor, so that the die may be adjusted and the space between the compressing-die and the carrying-dies be varied to accommodate the thickness of the buckle to be tongued. The arbor is held against upward movement by a set-screw n' , arranged in a threaded opening in the cross-bar d . 70

I claim as my invention—

1. In a machine for tonguing buckles, the combination, with a bending or compressing die, of a traveling die carrying the buckle and co-operating with said compressing-die, substantially as set forth. 80

2. In a machine for tonguing buckles, the combination, with a movable bending or compressing die, of a traveling die carrying the buckle and co-operating with said compressing-die, substantially as set forth. 85

3. In a machine for tonguing buckles, the combination, with an oscillating bending or compressing die, of a traveling die carrying the buckle and co-operating with the compressing-die, substantially as set forth. 90

4. In a buckle-tonguing machine, the combination, with a traveling or carrying die, of an oscillating compressing-die operating in conjunction with said traveling die and a spring whereby the oscillating die is returned to its normal position upon clearing the traveling die, substantially as set forth. 95

100 5. In a buckle-tonguing machine, the combination, with a traveling or carrying die, of an oscillating compressing-die operating in conjunction with said traveling die, a spring whereby the oscillating die is returned to its normal position upon clearing the traveling die, and a stop whereby the return movement of the compressing-die is limited, substantially as set forth.

6. In a machine for tonguing buckles, the combination, with a compressing-die, of a die carrying the buckle and a revolving disk to which said die is attached, substantially as set forth. 110

115 7. In a machine for tonguing buckles, the combination, with a movable bending or compressing die, of a traveling die carrying the buckle and having a seat for receiving the buckle and its tongue, substantially as set forth.

120 8. In a buckle-tonguing machine, the combination, with a compressing die having a bending-recess, of a traveling die co-operating with the compressing-die and having a buckle-seat, substantially as set forth. 125

9. In a buckle-tonguing machine, the combination, with a compressing-die, of a carrying-die having a transverse recess or depression for receiving one of the cross-bars of the buckle, substantially as set forth.

130 10. In a buckle-tonguing machine, the combination, with a compressing-die, of a carrying-die having a transverse recess or depression for receiving one of the cross-bars of the

buckle and a longitudinal recess for receiving the tongue of the buckle, substantially as set forth.

11. In a buckle-tonguing machine, the combination, with a traveling carrying-die, of a pivoted compressing-die provided with a shoulder or projection against which the traveling die strikes and whereby the compressing-die is swung on its pivot, substantially as set forth.

12. In a buckle-tonguing machine, the combination, with a traveling carrying-die, of a compressing-die co-operating with the traveling die and made adjustable toward and from the traveling die, substantially as set forth.

13. In a buckle-tonguing machine, the combination, with the stationary frame having an elongated opening or slot, of an adjustable compressing-die mounted on an arbor clamped in said slot and a set-screw bearing ²⁰ against said arbor, substantially as set forth.

Witness my hand this 19th day of March, 1889.

ADOLPH SAMSON.
